CLAIM

The ornamental design for product packaging, as shown and described.

DESCRIPTION

FIG. 1 is a perspective view of a product packaging showing our new design;

FIG. 2 is a front elevational view thereof;

FIG. 3 is a right side elevational view thereof;

FIG. 4 is a top plan view thereof; and,

FIG. 5 is a bottom plan view thereof.

The broken line showing of various regions, the unshaded portions therein, and the remainder of the product packaging is for illustrative purposes only and forms no part of the claimed design.
